UNITED STATES PATENT OFFICE

EMIL NEWBERG, OF BROCKTON, MASSACHUSETTS

DUPLEX WRENCH

Application filed April 14, 1928. Serial No. 270,105.

This invention relates to a wrench composed of a shank and heads formed on opposite ends thereof, the heads having flat parallel sides and nut-engaging openings extending through the sides, each head being formed to be grasped by a hand of the user, the arrangement being such that when one head is grasped, the other head is exposed and may be manipulated by the grasping hand to turn a nut.

Heretofore in a wrench of this character the sides of each head have been parallel with those of the other head, the side being in common planes. When the exposed head is in position relative to the grasping hand to properly turn a nut, the grasped head stands edgewise to the palm and fingers of the hand, so that the only bearings presented by the grasped head to the palm and fingers are the relatively narrow edges of said head. These edges indent and cause uncomfortable and sometimes injurious pressure on the palm and fingers, liable to cause callouses and sores when the wrench is frequently grasped by the same hand.

The chief object of the invention is to obviate the above-mentioned liability and enable the user to manipulate the wrench without discomfort.

30 Other objects will hereinafter appear.

Of the accompanying drawings forming a part of this specification,—

Figure 1 is a side view of a duplex wrench embodying the invention.

35 Figure 2 is a side view of the head, an edge view of which is shown by Figure 1.

Figure 3 shows in perspective the wrench shown by Figures 1 and 2, and a hand partly closed on the same.

40 The same reference characters indicate the same parts in all of the figures.

In the drawings, 12 designates the shank, and 13, 14 the heads formed on opposite ends of the shank. Each head has substantially flat and parallel sides, and an opening 15, extending through the sides, edges of said opening forming nut-engaging jaws. The form of each head is such that it is adapted to be grasped by a hand of the user, to manipulate 45 the wrench, the length of the wrench being

such that the other head is exposed. The operative position of the exposed head relative to the grasping hand should be such in any wrench of this character that the walls of the opening 15 in the exposed head may be conveniently applied to a nut, and the wrench may be caused to turn the nut by a swinging movement of the hand and wrench in a direction at right angles to the axis of the nut. The shank is oblong in cross section and has relatively wide sides and narrow edges.

55 A wrench which includes the shank and heads characterized as above stated, is in common use, the sides of each head being in the same planes with the sides of the other head, so that when the exposed head is in the proper position relative to the hand, the grasped head causes uncomfortable pressure on the palm and fingers of the hand.

65 My invention is characterized by the fact that the shank is twisted to locate the sides of one head substantially at right angles to those of the other, substantially a quarter twist being imparted to the shank, as best shown by Figure 1, said twist providing wind- 75

ing bearings for digits of an operating hand pinching the shank adjacent a head, as indicated by Figure 3. The arrangement is such that when the portion including the winding 80 bearings is pinched as shown, the palm of the operating hand bears on a flat side of one head, and is enabled to advantageously exert pressure thereon, causing the head adjacent the pinched portion and projecting from the hand, to turn a nut with which it is engaged.

85 By advantageously I mean that pressure exerted by the palm on the flat side of a head does not cause discomfort to the operator, and is not liable, when often repeated, to cause a sore or a callous on the palm. The operator is therefore enabled to press harder on the wrench and exert greater turning force on the nut than he could if obliged to exert pressure on a narrow edge face of a head as heretofore.

90 The form of the wrench characterized as above stated is such that the exposed head is held in proper position relative to the hand to turn a nut with which it is engaged when a 100

swinging movement is imparted to the wrench.

The described relative arrangement of the heads is preferably accomplished by first making the wrench in the usual form, the sides of each head being parallel with those of the other, and the sides of the shank substantially flat, and then twisting the shank until the sides of one head are substantially 10 at right angles with those of the other, as shown by Figures 1 and 3.

It is to be understood that when the wrench is in use, the fingers are closed on the shank and the grasped head more fully than as 15 shown by Figure 3, this figure being intended to illustrate the bearing of the inner side of the grasped head on the palm.

I claim:

A duplex wrench comprising a shank and 20 two flat-sided nut-engaging heads formed on opposite ends thereof, the shank being twisted to locate the sides of one head substantially at right angles to those of the other and provide the shank with winding bearings for 25 digits of an operating hand pinching the shank adjacent one of the heads, the arrangement being such that when the shank is thus pinched, the palm of the hand bears on the flat side of the other head and is enabled to 30 advantageously exert pressure thereon, causing the head adjacent the pinched portion to turn a nut with which it is engaged.

In testimony whereof I have affixed my signature.
